UNITED STATES PATENT OFFICE.

NATHANIEL P. PRATT, OF ATLANTA, GEORGIA.

EXHAUSTER.

SPECIFICATION forming part of Letters Patent No. 602,770, dated April 19, 1898.

Application filed February 13, 1897. Serial No. 623,313. (No model.)

To all whom it may concern:

Be it known that I, NATHANIEL P. PRATT, a citizen of the United States, residing at Atlanta, in the county of Fulton and State of Georgia, have invented certain new and useful Improvements in Exhausters; and I do hereby declare the following to be a full, clear, and exact description of the invention, such as will enable others skilled in the art to which it appertains to make and use the same.

This invention relates to exhausters.

The objects are to provide an exhauster adapted particularly in use for handling corrosive gases, either acid or alkaline, in which those parts subjected to direct contact with the gases will be shielded from the corrosive action thereof; to provide an exhauster having a casing of such construction as to permit of easy and ready access to the interior thereof for the purpose of removing the blast-wheel without disturbing the permanent parts of the apparatus; to provide simple and effective means for holding the blast-wheel on the shaft and for shielding such means from the action of the gases, and, finally, to provide an exhauster which shall be simple in construction, durable and efficient in use, and which may be constructed at a nominal figure.

In an exhauster characterized by my invention I provide a blast-wheel casing, cast or made by hand, of an alloy of lead and antimony or other non-corrosive materials. This casing is constructed of two parts, one part of which may be designated as the "stationary" portion and the other part as the "removable" portion. The stationary portion is provided with the usual entry and exit flues, and these latter, for the purpose of preventing escape of gases at these points, may be burned to the stationary portion of the casing or may be provided with flanges to be bolted to similar flanges on the said stationary portion. The stationary portion is also provided with a suitable stanchion on one side opposite the entry-flue which supports the boxes or bearings in which works the blast-wheel shaft, the said shaft being provided with a non-corrosive protecting-sleeve to shield the shaft against the corrosive action of gases which may escape at this point and

which would tend to destroy the exterior portion of the shaft. This stationary portion may be constructed of two sections, as usual, (though it may be made in one or any number of sections,) and be held together by bolts passing through flanges provided for the purpose, an acid-tight joint being provided by interposing a suitable packing or cement between the flanges, or by burning these parts together, as will be understood. The removable portion of the casing may occupy the upper part thereof to one side the entry or exit flue, or both, as may be preferred, and is secured to said lower portion by bolts passing through flanges provided for the purpose, suitable packing or cement being interposed between the flanges to present a tight joint, this removable portion, as also the stationary portion, being provided on one side with a section of a stuffing-box in which the sleeve-covered shaft works. The removable portion is of such size with relation to the stationary portion that upon its removal the interior of the casing will be exposed to view, so that, if desired, the blast-wheel may be removed.

The blast-wheel is to be constructed of any suitable non-corrosive materials and should possess sufficient rigidity to present the requisite strength for speed without danger of losing its shape. This wheel may be secured to the shaft by which it is driven in any suitable manner, as by casting the wheel around a right and left hand threaded bushing, which may also be provided with keys, and securing this bushing to the shaft by a key or by so shaping the shaft and the bushing as to prevent the turning of the shaft therein, or the keys may be dispensed with and the bushing serve to hold the wheel in place, or the bushing may be simply roughened or have projecting points, which will sink into the metal of the wheel when the same is cast around it, or the shaft may be rounded and fixed in the bushing by an ordinary key, or the key may be dispensed with, and the shaft may be made square, triangular, hexagonal, or otherwise in cross-section, the bushing being shaped to fit the shaft, or the hub may be soldered to the shaft.

The removable portion of the casing may

be constructed in one or more sections, preferably in one, and the flange or flanges by which it is secured to the stationary portion may extend only to the entry or exit flues, or may extend over and join a similar flange on either one of these flues or both.

In order to facilitate access to the blast-wheel, the same is free from any support at one end, so that by removing the section of the casing just described the portion of the stuffing-box attached will come apart with it and the shaft and its blast-wheel may be lifted out.

The shaft on which the blast-wheel is mounted works in bearings entirely removed and free from the casing, so that they will be readily accessible for the purpose of oiling or otherwise.

Further and more specific details of construction will be hereinafter described.

In the accompanying drawings, forming a part of the specification, and in which like letters of reference indicate corresponding parts, I have illustrated a form of embodiment of my invention, although it is to be understood that other forms of embodiment thereof may be employed without departing from the spirit of my invention.

In the drawings, Figure 1 is a view in side elevation, displaying the exhauster as it appears when set up for use, the view being taken from the pulley side of the casing. Fig. 2 is a view in plan. Fig. 3 is a view in end elevation. Fig. 4 is a view in elevation of the blast-wheel. Fig. 5 is a view in vertical section, showing more particularly the manner in which the blast-wheel is secured to the shaft. Fig. 6 is a detached view of the right and left hand threaded bushing for holding the wheel in place on the shaft; and Fig. 7 is a view in transverse section, showing more particularly the manner in which the sections of the casing are joined.

Referring to the drawings, A designates the stationary portion of the casing, and A² the removable portion thereof. The stationary portion is provided on one side with an entry-flue a and at its periphery with an exit-flue a², as usual, it being understood that I do not limit myself to the precise location of these flues, as their position may be altered without departing from the spirit of my invention. The stationary portion of the exhauster is constructed of one or more sections, and if more than one are employed they are secured together by flanges a³, through which pass bolts a⁴ for holding the parts assembled, these flanges being packed, cemented, or burned together in any well-known manner to prevent a tight joint. In this form of my invention the stationary portion is shown provided with legs or standards a⁵ for supporting the casing; but it is to be understood that these legs may be dispensed with and the casing supported upon an ordinary base.

The removable portion A² may be in one piece, or it may be made of more pieces and is provided with flanges a⁶ on its body and with side flanges a⁷, mating with similar flanges a⁸ on the stationary portion of the casing, and through these latter flanges bolts are passed for holding the two parts assembled, any suitable packing, such as indestructible putty or the like, being placed between the flanges for the purpose of making a tight joint. It is to be understood that the location of the flanges a⁷ a⁸ may be changed and may be either straight or curved. The flanges a⁶ are also to be burned, packed, or cemented together to present a tight joint. The flanges a⁷ a⁸ are to be so formed as to avoid interference with the entry-flue on that side of the casing, and on the opposite side of the casing these flanges are to be curved into the shaft-opening, as at a⁹, and to be provided each with a section of a stuffing-box for the shaft. The objects of curving or projecting the portion a⁹ of the casing in toward the entry-flue are twofold. First, to have the bearing or stuffing box as near the blast-wheel as possible to reduce leverage and thus prevent wobbling and eccentric movement of the wheel with attendant vibrations and consequent injurious racking of the casing, and, second, to have the portion a⁹ correspond with the concavity of the disk of the blast-wheel to prevent, as far as possible, escape of gases from the casing through the stuffing-box by causing the gases to be projected practically from one side of the blast-wheel. This peculiar formation of the casing is highly advantageous and increases the usefulness and life of the device.

As will be noted by reference to Fig. 3, the inner end of the blast-wheel drive-shaft, or that end next to the inlet-opening, is not supported, as it is essential that the inlet-flue should be free from any obstruction, and this arrangement, due to the weight of the blast-wheel, puts a great strain on this end of the drive-shaft, and without the novel means of supporting the same, as shown, the leverage would be so great that in a short time the wheel would wobble and have eccentric movement, and thereby tend rapidly to destroy the bearings.

By the peculiar manner of curving the sides of the casing inward around the shaft on the pulley side to present two members of a stuffing-box admission of air from without or escape of gas from within is obviated, and by having the journal-boxes as near the plane of rotation of the wheel as possible the wheel is supported, braced, and steadied, so that under all conditions of use it will run in a true circle.

It will be apparent that by removing the bolts for holding the flanges a⁷ a⁸ together and detaching the removable portion of the casing access to the interior thereof may be had without interfering with the fixed parts

of the casing—that is to say, with the stationary portion thereof—and with the entry and exit flues.

The blast-wheel B is to be made of any suitable material combining strength with non-corrosive qualities, and may be of any preferred shape for the purpose. The hub b of this wheel has in this instance fitted within it a bushing C, provided with right and left hand threads, this bushing being held in place within the hub by having the metal thereof cast around it. The shaft D of the blast-wheel is provided at one end with a collar d, against which the bushing C and the outside 15 projecting end of the hub abut, said shaft being in this instance held against turning by being united, as by keying into the bushing, the bushing being made really a part of the blast-wheel hub, or by lightly tinning the 20 surface of the same before the blast-wheel is cast around it. A key d^2 may be inserted between the bushing and the shaft and similar keys c between the bushing and the hub to hold these two securely assembled; but, 25 as before stated, the particular manner of holding the blast-wheel in place on the shaft may be varied at will. The outer end of the shaft is threaded, and on this threaded portion are turned two nuts d^3 d^4 , the latter constituting a locking-nut, these nuts serving to 30 force the hub tightly against the collar d and thereby further prevent the wheel from turning on the shaft. In order to protect the end of the shaft carrying the nuts d^3 d^4 and also 35 the nuts from the corrosive action of the gases, a cap b² is burned onto the hub of the blast-wheel and incloses these nuts. When the wheel is to be removed from the shaft, this cap may be cut off and the nuts and key 40 removed in an obvious manner to effect release of the wheel.

The shaft D is supported exteriorly of the casing upon a bed E, having journal-boxes e, in which the shaft works, these boxes being 45 provided with suitable openings e², by which oil may be supplied to the shaft, the latter also being provided with a pulley e³, by which the wheel may be driven.

In order to remove the liquids resulting 50 from condensation of gases, a drip-pipe F is provided at the bottom of the casing, by which the liquid may be removed as rapidly as generated and caught in a suitable receptacle, as G.

It is to be understood that I do not limit 55 my invention to the materials and to the particular use described, as the apparatus is adapted for handling gases other than those described or for air. In the latter instance the casing may be made of wood, paper, or 60 other suitable materials instead of metal.

Having thus fully described my invention, what I claim as new, and desire to secure by Letters Patent of the United States, is—

1. An exhaust-casing comprising a stationary portion provided on one side with an entry-flue and at its periphery with an exit-

flue, and a peripherally-removable portion extending to the axis of and impermeably secured to the stationary portion, the removable portion being of such size that, when removed, 70 an opening is left, through which the blast-wheel and its shaft can be taken out without detaching either of the flues, substantially as described.

2. An exhaust-casing comprising a stationary portion provided on one side with an entry-flue and at its periphery with an exit-flue, and a peripherally-removable portion extending to the axis of and impermeably secured to the stationary portion, a blast-wheel 80 mounted in the stationary portion opposite the entry-flue, and a stuffing-box arranged partly on the stationary portion and partly on the removable portion for preventing admission of air from without or escape of gas 85 from within, the removable portion of the casing being of such size that, when removed, an opening is left, through which the blast-wheel and its shaft can be taken out without interference with either of the flues, substan- 90 tially as described.

3. An exhaust comprising a stationary portion having an entry and an exit flue, and a removable portion, the sides of the two portions, opposite the entry-flue, being curved or 95 bent inward to present two members of a stuffing-box, substantially as described.

4. An exhaust comprising a stationary portion having an entry and an exit flue, and a removable portion, the sides of the two portions, opposite the entry-flue, being curved or 100 bent inward to present two members of a stuffing-box, a shaft running in the stuffing-box, and a blast-wheel supported on the shaft in juxtaposition to the stuffing-box, substan- 105 tially as described.

5. An exhaust comprising a stationary portion having an entry and an exit flue impermeably secured thereto, and a removable portion, the removable portion being adapted 110 to be separated from the stationary portion without interference with any of the parts of the latter, the sides of the two portions, opposite the entry-flue, being curved or bent inward to present two members of a stuffing-box, a blast-wheel mounted within the casing 115 and having a shaft running in the stuffing-box, the end of the shaft, opposite the entry-flue, being unsupported, substantially as described.

6. An exhaust-casing comprising a stationary portion provided on one side with an entry-flue and at its periphery with an exit-flue, and a peripherally-removable portion extending to the axis of and impermeably 125 secured to the stationary portion, the removable portion being of such size that, when removed, an opening is left, through which the blast-wheel and its shaft can be taken out without interference with either of the flues, 130 and a drip-pipe connected with the casing, substantially as described.

7. In an exhauster, a shaft, a blast-wheel secured thereto by solder or the like, nuts secured on one end of the shaft for holding the wheel in place, and a non-corrosive cap or casing inclosing the nuts and the end of the shaft, substantially as described.

8. In an exhauster, the combination with a shaft, of a blast-wheel, a right and left hand threaded bushing secured to the hub of the

wheel and to the shaft, and keys inserted between the bushing and shaft, substantially as described.

In testimony whereof I affix my signature in presence of two witnesses.

NATHANIEL P. PRATT.
